PASSING BALL

Joseph Klecka, Downers Grove, Ill.

Application June 12, 1937, Serial No. 147,959

1 Claim. (Cl. 273—58)

My invention relates to an especially new and improved passing object or missile in the form of a hand-ball of the type calculated to promote wholesome fun and amusement when thrown 5 from or at the participants in a free-for-all game.

The principal object of the invention is to provide such a device to be used in recreational activities to promote an outdoor sport for healthy 10 exercise and recreation.

Another object of the invention is to provide such a device in which novel means are employed embodying a ball-like pellet constructed of excelsior, sawdust, or other soft material, and having 15 a layer of raw cotton, and a confining jacket for the raw cotton, and having a plush-like outer finish, which will reduce the tendency to injure a person when struck by the said ball-like pellet.

Another object of the invention is to provide a 20 device which is characterized by simplicity, efficient construction and inexpensiveness to manufacture.

Other objects and advantages will be apparent during the following description.

25 With the foregoing in view, the invention resides in the novel subject matter hereinafter described and claimed, the description being supplemented by the accompanying drawing, in which:

30 Figure 1 is a top plan view of the device partly broken away; and

Figure 2 is a central sectional view taken on the line 2—2 of Figure 1.

In the drawing, wherein for the purpose of 35 illustration, is shown a preferred embodiment of the invention, the numeral 3 designates the ball-like pellet constructed in accordance with the principles of the present invention, which may be either circular, rectangular, or any preferred form. The numeral 4 designates the core or filling. The numeral 5 designates the raw cotton padding, and the numeral 6 designates the jacket 40

or covering, which may be made of velvet, velour, or equivalent material.

In constructing my ball-like pellet 3 I provide a core or filling 4 of sawdust, straw, or equivalent material. I then provide a surrounding inclosure 5 of raw cotton or equivalent material 5, which serves as a padding, and has a tendency to make the object soft and pliable. The ball-like pellet 3 is then finished by providing a confining jacket 6 which is preferably made of velvet, velour, or other soft material. After the article is thus built up from the core or filling 4, the padding of raw cotton 5, the sections of the jacket or covering 6 are suitably sewed or otherwise joined together, as indicated by the numeral 7. 15

From the foregoing it will be apparent that I have produced a device which is novel and unique, and one which will engender a spirit of activity to promote an outdoor sport having recreational benefits and healthful exercise. 20

It is thought that persons skilled in the art to which the invention relates will be able to obtain a clear understanding of the invention after considering the description in connection with the drawing. Therefore, a more lengthy description 25 is regarded as unnecessary.

Since excellent results are obtainable from the details disclosed, they are preferably followed. However, within the scope of the claimed invention, numerous modifications may of course be 30 made.

I claim:

In a game and fun provoking missile, a hand ball comprising a padded filler of sawdust, a surrounding layer of raw cotton contained within 35 said core, and an outer soft surfaced jacket having plush-like finish and constituting a protective covering for said sawdust and said cotton, said sawdust filler, cotton and confining jacket being compressed to form a soft hand ball, and having 40 a flat-like form, the sections of said jacket being sewed together.

JOSEPH KLECKA.
